1 Claim. (Cl. 103—126)

The invention relates to an arrangement for equalization and reduction of the pressure upon a stuffing box for the shaft of a rotor of a pump, particularly a pump adapted for the pumping of stuff of a high viscosity or consistency, such as fibrous suspensions, and in which the rotor is subjected to different pressures on opposite sides of its shaft.

In known pumps of said kind the stuffing box for the rotor shaft projecting through the pump casing is influenced by a pressure which is unevenly distributed over the circumference thereof, a condition which has proved to give rise to rapid wear and leakage. The object of the invention is to eliminate said drawback and to equalize the pressure upon the stuffing box over its circumference and simultaneously to reduce said pressure to the lowest pressure present in the pump. According to the invention said object is attained essentially thereby that in the wall of the pump casing there is a groove extending all around the shaft, which groove on the high-pressure side of the pump is covered by the plane end face of the rotor moving closely adjacent to said wall and which groove on the low-pressure side is widened so as to extend beyond said end face, whereby the pressure prevailing on said last-mentioned side gets free access to the groove and can spread therewith. In order to prevent clogging of said groove a projection may be provided on the rotor or its shaft, which projection with a suitable clearance fits to the narrowest cross-section of the groove.

An embodiment of the arrangement according to the invention will be more closely described herein below with reference to the accompanying drawing, in which FIG. 1 is a vertical cross-sectional view of a pump equipped with the arrangement according to the invention, FIG. 2 is a horizontal cross-sectional view of one end of the pump, and FIG. 3 is a part of FIG. 2 shown on an enlarged scale.

The pump shown in the drawing is of the cog wheel type and comprises two rotors 11 and 13 which are arranged parallelly and adjacent to each other and are inserted into a pump casing between the inlet side 17 thereof where a low pressure prevails, and its outlet side 19 where a higher pressure prevails in operation due to the action of the pump. The rotors are shaped with projecting cams or knives 21 each cooperating with a pertaining flute-like depression 23 in the face of the opposite rotor in such a manner that a seal is maintained between the rotors during their rotation. The cams 21 also cooperate with cylindrically curved walls of the pump casing in such a manner that a seal is maintained between the high-pressure side and the low-pressure side of the pump on the far sides of the rotors. When the rotors are driven in the direction of the arrow 25, successive batches of the stuff to be pumped, e.g. high-consistency cellulosic pulp, are transferred from the inlet side to the outlet side of the pump by being enclosed within and carried forth in compartments successively formed between the rotors and

2

the cylindrical wall of the housing, whereas the same number of batches, but each of a considerably smaller content, are carried back through compartments successively formed between the rotors.

The casing 15 has interior plane side walls 27, and the rotors have corresponding plane end faces 29 moving along said walls as closely as possible thereto. At either end the rotors are provided with a shaft stud 31 extending through a corresponding aperture in the wall and being journaled, e.g. by means of a ball bearing 33, in a bearing bracket or similar attached to the pump casing. Keyed to one end of either rotor is a gear wheel 35 for driving the rotors. The part of the shaft stud 31 which is located closest to the rotor end and which preferably is cylindrical, is sealed to an annular flange 37 upon the wall of the pump casing by means of a stuffing box which may be composed of a plurality of rings 39 of a suitable stuffing material put upon the shaft stud 31 and let into a bore in said annular flange and clamped thereto. Inserted between two of said stuffing rings is an apertured ring 41 which communicates with a bore 43 in the flange 37, said bore forming an outlet for liquid which may have leaked past the stuffing rings 39 on the inner side of said apertured ring.

According to the invention, a groove 47 is provided in the wall 27 in the immediate vicinity of the bore therein for the shaft stud. On the high-pressure side of the pump said groove which preferably is of a rectangular cross-section, is so narrow measured in the radial direction of the rotor that it is covered by the end face 29 of the rotor. The clearance 49 between the faces 27 and 29 is too slight to allow passage of fibre material from the high-pressure side into said groove 47. Conversely, on the low-pressure side of the pump the groove is widened to such an extent that great parts thereof are not covered by the end face 29 of the rotor, the pressure prevailing on the low-pressure side of the pump having access to the groove. Said pressure propagates into the narrow part of the groove on the high-pressure side of the pump, so that the pressure everywhere in the groove is the same and equal to the lowest pressure present in the pump. In this manner, the pressure upon the stuffing box 39 is considerably reduced and besides, said pressure is equal all around the circumference. Preferably, the measure of the groove in the axial direction of the rotor is uniform.

Arranged in the angle between the shaft stud 31 and the plane end face 29 is a die, boss or similar projection 51 which is shaped to fit into the narrowest part of the groove 47 with a suitable clearance. The die may be integral with the rotor or may be manufactured separately and attached, e.g. welded, to the rotor or its shaft stud. During each revolution of the rotor said die moves through the narrow part of the groove and removes fibres which may have escaped therewith. In this manner the groove will always be held open all around and the pressure equalization maintained.

I claim:

Means for the equalization and reduction of the pressure upon a stuffing box for the shaft of a rotor of a pump, particularly a pump adapted for pumping of fibrous suspensions, and in which the rotor is subjected to different pressures on opposite sides of its shaft, comprising a groove in the wall of the pump casing and encircling said shaft, the groove on the high-pressure side of said rotor being

covered by the plane end face of the rotor movable close to said wall and the groove on the low-pressure side being widened to extend beyond said end face, so that the pressure prevailing on the low-pressure side has free access to the groove and can spread therein, said rotor being provided with a projection which fits with a suitable clearance to the narrowest cross-section of the groove and serves to prevent clogging of the same.
